UNITED STATES PATENT OFFICE.

EMILE ARSÈNE NOBLE, OF TROYES, FRANCE, ASSIGNOR TO SOCIETE ANONYME DES
ETABLISSEMENTS DELOSTAL FRERES, OF TROYES, AUBE, FRANCE.

STRAIGHT-BAR KNITTING MACHINE.

Application filed December 21, 1923, Serial No. 682,051, and in France January 5, 1923.

The present invention relates to a device which results in considerable friction losses and requires an exaggerated expense of power, especially for low stroke operations. Moreover, said means together with the stopping and locking devices are scattered throughout the whole length of the bars, which hinders the passage of the yarns and complicates the setting up of the stop and lock carrying means.

The said arrangement is essentially characterized in that it comprises:

1.—Two groups of fingers whose number is equal in each group to that of the thread carrier bars and secured to each end of the looping bar, each of said two groups acting in a given direction.

2.—A mechanism for returning the arms and changing the carrier bars permitting to automatically effect the various consecutive operations on a piece of goods by actuating one or more carrier bars.

3.—A disposition for guiding and strengthening the carrier bars at their ends by the adaptation of sheathing or lining thereto which receives the efforts caused by the thrust, the impact of the stops and the locking of said bars.

4.—The arrangement below the bars of the stops and the locking devices for obtaining the partial strokes of the carrier bars for carrying on, for instance, the heeling, splicing, or knitting of the upper part of the foot; as well as the unhooking of the locks for the departure of the carrier bars and the optional suppression of the stops allowing the bars to stroke between the outer selvages.

The said entraining arrangement allows of operating one or more carrier bars by means of a single device, thus replacing the counters and the striping apparatus actuating but a single bar, and the friction entraining devices used with the additional thread carriers for heels and splicing. The use of the said arrangement requires a special type of guides and of strengthening means for the bars, forming guideways at the ends thereof, and a special disposition of removable stops for the heels and other reduced strokes of the thread carriers, the practical arrangement of said stop offering substantial tappets and provides for a reliable locking, while eliminating all vibration of the thread carriers. In certain known knitting machines the carrier-bars are drawn along by friction by means of devices cooperating with the looping bar and drawn along with it. Said arrangement re-

The appended drawing shows by way of example a constructional form of the entraining device according to our invention, as applied to a cotton knitting machine of the plain stitch type for narrowed hosiery wherein the working of the thread carriers offers the greatest variation, this manufacture requiring in some cases as many as five bars on various strokes for forming the loops of the same row.

Figs. 1 and 3 are elevational views of the entraining device, on both sides thereof, and Fig. 2 is a side view of the same.

Fig. 4 is an elevational view of the locking devices and stops, with parts broken away.

Fig. 5 is a section on the line A—A of Fig. 4 showing the guides and the strengthenings of the carrier bars.

Figs. 6, 7, 8, 9 show the mechanism for changing the carrier bars, in side elevation.

Fig. 10 is a front view and Fig. 11 a plan view of the same.

Fig. 12 is a modified form of the entraining device.

Fig. 13 shows an arrangement by which the cylinders are replaced by an attachment comprising sprocket-wheels and stud carrying chains.

Fig. 14 shows a detail view illustrating the use of the handles 39.

As shown in the drawings, the fingers 1, (Figs. 1, 2, 3) whose number is equal to that of the carrier bars, are pivoted upon an axle and are mounted on a movable common frame 2. They are maintained by the rods 3 set under the action of push springs 4 and engaging V-shaped notches made in said fingers. There are two frames 2 and they are connected respectively by the supports 5 to each end of the looping bar and guided by a fixed guideway 6. The thrust upon the carrier bars 7 takes place through the medium of the screws 8 mounted upon the said bars. The said screws serve to adjust the distance between the thread carriers and

the sinkers forming the loops. The thrust effort upon the carrier bars will depend upon the adjustment of the springs 4 which is ensured by the screws 9, the corresponding ends of the rods 3 being adapted to slide within axial holes in said screws.

Fig. 12 shows an arrangement in which the rods 3 are replaced by levers 10 urged by the springs 11. The ratio of the lever arms permits, in some cases, a greater amount of thrust.

According to the preceding, the frames 2 provided with the fingers 1 will be drawn along by the slur-cock throughout the whole stroke thereof and each of said frames impels in a given direction one or more carrier bars by means of those of the fingers 1 which are in the lower position.

The various control of the entraining operations of the carrier bars is as follows:

When one of the actuated carrier bars engages its stop-piece, the finger 1 will pivot about, thus releasing the rod 3 from the notch of said finger, and the latter will assume the position shown in Fig. 3 which it maintains during the return stroke. At the end of this return stroke, the said fingers engage the strikers 12, Figs. 6, 10 and 11, which bear upon a stationary edge of the fixed support 16 and return said fingers into their operative position. If the said strikers are in the raised position, as shown in 12', Figs. 10 and 11, they will recede under the pressure of the fingers, thus compressing the springs 13; in this event the said fingers will not be turned down and will not be operative during their return stroke.

The operation of raising or lowering the said strikers 12 is obtained, at each end of the machine, by means of the cams 15 mounted upon a cylinder 17 and controlling the strikers through the medium of the levers 14. Both cylinders 17 are keyed to each end of a shaft 18 and they will act by the same disposition of cams 15 in order to raise or lower the same strikers whereby the same bars are actuated in either direction.

The two cam cylinders remain stationary, being held by a ratchet 19 and a pawl 20, as long as it is desired to make use of the same carrier bars.

The operation of changing the carrier bars, which changing is required for effecting the different operations of striping, plating, splicing, feeding the heel, etc., is effected by turning the two cylinders from one division to another, each of said divisions being provided with a row of cams of suitable disposition according to the sequence of the various operations.

In the arrangements here shown, each generatrix of the cylinder corresponding to each division of the same have adjacent each lever 14 suitable tapped holes adapted to

receive screws the heads of which form the said cams 15.

In practice, the cylinders will have upon their surface one or more combinations of cams which are necessary for the manufacture of the same piece of goods, which combinations may be changed by removing the said cam screws. For most complicated combinations, these cylinders may be replaced by sprocket-wheels entraining chains provided with studs such as are in common use for looms as shown in Fig. 13.

The changing of the operative carrier bars will be effected by hand or automatically. For hand operating, this is effected by the handle 21, Fig. 7, provided with a pawl and loosely revoluble on the shaft of the ratchet 19. For automatic operation, the movement is effected by the lever 22, Figs. 8 and 9, which is connected with said pawl by a link and is impelled by a cam 23 keyed to the driving shaft of the machine. The hook 24 which holds the whole mechanism in such a manner as to maintain the cam roller of the lever 22 out of the influence of the cam 23, is released by means of a cam placed upon the chain of a counting device, a means which is usually employed for analogous movements.

As concerns the guides and the reinforcing sheaths for the carrier bars, suitable sheathings or linings 25 are disposed upon the ends of these bars; they surround the latter on three sides and have edges which bear upon the guides 28 secured to the supports 29 and 30. The said sheathings carry on their upper face the entraining screws 8 above mentioned and on their lower face the screws 26 and 56 which may be locked in fixed position by lock-nuts 26' and 57. Let us consider the left end of the machine. The right end is symmetrical to the left. The screw 26 serves to regulate the stopping of the corresponding carrier bar against the stops 34 for the outer selvedges of the hose-legs and the screw 56 serves to lock the bar against the lock 33 for making the heels and for splicing.

The thrusts and the contact shocks will thus take place upon the said linings which serves also as guides; the bars thus reinforced can withstand all breaking strains.

The arrangement of stops and locks is carried out as follows. The supports 29, 30, 49 are secured to the frame, and upon the said supports are mounted the locks 34, 33 and the stops 58. 32 is modified part of the narrowing or covering sliding-carriage having thereon the support 29 and upon which support are mounted the locks used for the outer selvedges, 32 carries the stop 31. The said locks 33, 34 and stops 58 are vertically urged by the springs 35 and retained by the horizontal pins 37 secured to the supports. Suitable studs 36, 67, 77 mounted on the

locks 33 and 34, and upon the stops 58 respectively, are enabled to strike against the pins 37 in order to limit the stroke of the said locks and stops.

Supposing that Fig. 4 shows the arrangement at the left hand of the machine, and that a symmetrical arrangement is mounted at the right, the two following examples will set forth the operation of the said stops and locks.

a.—For stopping the carrier bars at the outer-left-hand selvedge of the goods, the nut 26' carried by the thread carrier bar will strike near the end of the left hand stroke of this bar against the inclined face of the upper part of the lock 34; thus the latter will descend in the support 29 in order to let the nut 26' and the screw 26 pass over said lock 34 so that the carrier bar may stop against the stop-screw 31 mounted on the narrowing carriage 32. At the same time, the screw 26 has passed over the lock 34 which rises again behind said screw 26, thus ensuring a tight holding of the latter and of the corresponding carrier bar.

b.—For the inner selvedge of the right heel, the screw 56 carried by the carrier-bar which moves from the right to the left, stops against a stop 33 on a support 30 disposed at the left hand of the machine; the locking takes place at the same time at the right-hand side of the machine by means of a lock disposed on the right hand support symmetrical to the left-hand support 30 shown in Fig. 4. The symmetrical operations take place for making the inner selvedge of the left heel.

The following part of the description shows the adaptation of the various working manner of the carrier-bars.

If one of the carrier-bars is to be stopped alternately at the right and at the left, and otherwise than for the selvedges, in order to feed the upper part of the foot or the loop rows between the heels, the following arrangement is employed (Fig. 4). The stopping at the end of the right hand motion takes place between the lock-nut 57 mounted on the carrier bar and the adjustable stop-screw 53 mounted on a stop 58 which is slidable in a support 49 secured to the frame; the locking of the bar is effected by the adjustable screw 56 acting upon the lock 33 of the support 30. The stopping and the locking at the end of the left-hand motion of the bar will take place in the same manner but at the right-hand side of the machine.

The locks must be released in order to provide for the restarting of the carrier bars. For this end the lever 43, Fig. 4, which is pivoted to the support 29, carries a roller 45 and a pin 46 which is adapted to bear upon the pin 36 of the lock 34. A cam 47 secured to the movable support 5 which follows the

motion of the slur-cock acts upon the roller 45 and lowers all the locks of the support 29. A lever 64 pivoted to the support 30 is provided with a roller 65 and a pin 66 which may bear upon the studs 67 of the locks 33. The roller 65 is actuated by a cam 48 pivoted at 68 to the movable support 5. During its left-hand stroke, the cam 48 raises the roller 65 and lowers the locks of the support 30. During the reverse stroke the said cam 48 strikes the roller 65 by means of its lower inclined plane so that the said cam will rise and pass over the roller 65.

The locks 33, as well as the stops 58 have to be permanently lowered when the corresponding bars travel over the whole stroke between the outer selvedges. This lowering is effected by means of curved rods 38, Fig. 4, operated by handles 39 and held in the hooked position by the springs 41 and 73 shown in Fig. 4 and cooperating with catches 74 secured on said rods 38 and shown in Fig. 14. The whole device is mounted upon supports 40 secured to the frame. The various rods 38 act upon the studs 67 of the locks 33 and upon the pins 77 of the stops 58. In order to return the said stops and locks into their operative position, it suffices to disengage the catch 74 by means of the knobs 42 provided for this purpose; the rods 38 will resume their top position under the action of the springs 41 and 73 mounted round the said rods within the supports 40.

Having now described my invention what I claim as new and desire to secure by Letters Patent is:

1. In a straight knitting machine, the combination of means comprising thread carrier-bars and a looping bar with frames moving above said carrier-bars, whereby the motion of the looping bar is transmitted simultaneously to a number of thread carrier-bars, said means consisting of two groups of pivoting fingers whose number is equal to the number of thread carrier-bars, each of said groups being adapted to act in a given direction, said fingers being yieldingly secured in determined angular positions, stopping and locking devices adapted to limit the stroke of the thread carrier-bars and located below said carrier-bars, whereby each finger is overturned into its inoperative position at the end of the stroke by the corresponding carrier-bar, means controlling the setting-up of the pivoting fingers whereby several bars are adapted to be simultaneously driven along for independent strokes of different amplitudes.

2. In a straight bar knitting machine the combination of thread carrier-bars and a looping bar, with frames moving above said carrier bars and drawn along by said looping bar, fingers pivotally mounted on said frames, means for yieldingly maintaining said fingers in determined angular positions,

- means secured to said carrier bars and adapted to be engaged by those of said fingers being in their operative angular position whereby said carrier bars are driven along in either direction and the same fingers overturned in their inoperative position when said carrier bars are stopped, strikers located respectively at both ends of the stroke of each carrier bar and adapted to be engaged by said fingers, means for locking said strikers whereby the locked strikers overturn the corresponding fingers into their operative position, means for allowing the unlocked strikers to yield under the thrust of the corresponding fingers, rocking levers for controlling the locking of said strikers, a cam arrangement for controlling said levers whereby the carrier bars to be driven may be selected, and means located below the carrier bars for adjusting the stroke of the same. 35
10. engaged by said fingers, means for locking said strikers whereby the locked strikers overturn the corresponding fingers into their operative position, means for allowing the unlocked strikers to yield under the thrust of the corresponding fingers, means for controlling the locking of said strikers and means located below the carrier bars for adjusting the stroke of the same. 40
15. 3. In a straight bar knitting machine, the combination of thread carrier bars and a looping bar, with frames moving above said carrier bars and drawn along by said looping bar, fingers pivotally mounted on said frames, means for yieldingly maintain said fingers in determined angular positions, means secured to said carrier bars and adapted to be engaged by those of said fingers being in their operative angular positions whereby said carrier bars are driven along in either direction and the same fingers overturned in their inoperative position when said carrier bars are stopped, strikers located respectively at both ends of the stroke of each carrier bar and adapted to be engaged by said fingers, means for locking said strikers whereby the locked strikers overturn the corresponding fingers into their operative position, means for allowing the unlocked strikers to yield under the thrust of the corresponding fingers, rocking levers for controlling the locking of said strikers, a cam arrangement for controlling said levers whereby the carrier bars to be driven may be selected, and means located below the carrier bars for adjusting the stroke of the same. 45
20. 4. In a straight bar knitting machine the combination of thread carrier bars and a looping bar, with fingers moving above said carrier bars and driven along by said looping bar, linings for reinforcing and guiding said carrier bars, adjustable screws secured to said linings and upon which said fingers are adapted to stroke whereby the carrier bars may be driven in either direction, means located at both ends of the machine for selecting the carrier bars to be driven, stopping and locking devices located at both ends and below each carrier bar for varying the stroke of the same and adjustable screws secured to said linings and cooperating with said stopping and locking devices whereby the stroke of said carrier bars may be adjusted. 50
25. 5. In testimony whereof I have signed my name to this specification. 55
30. EMILE ARSÈNE NOBLE. 60
